(57) **CLAIM**

The ornamental design for a container for laundry detergent, as shown and described.

DESCRIPTION

FIG. 1 is a perspective top view of a first embodiment of a container for laundry detergent in accordance with the new design;

FIG. 2 is a left side view of the container for laundry detergent of FIG. 1;

FIG. 3 is a right side of the container for laundry detergent of FIG. 1;

FIG. 4 is a back view of the container for laundry detergent of FIG. 1;

FIG. 5 is a front view of the container for laundry detergent of FIG. 1;

FIG. 6 is a top view of the container for laundry detergent of FIG. 1;

FIG. 7 is a bottom view of the container for laundry detergent of FIG. 1;

FIG. 8 is a perspective top view of a second embodiment of a container for laundry detergent in accordance with the new design;

FIG. 9 is a left side view of the container for laundry detergent of FIG. 8;

FIG. 10 is a right side view of the container for laundry detergent of FIG. 8;

FIG. 11 is a back view of the container for laundry detergent of FIG. 8;

FIG. 12 is a front view of the container for laundry detergent of FIG. 8;

FIG. 13 is a top view of the container for laundry detergent of FIG. 8; and,

FIG. 14 is a bottom view of the container for laundry detergent of FIG. 8.

The broken lines in the drawings depict portions of the container for laundry detergent that form no part of the claimed design.
